UNITED STATES PATENT OFFICE.

HORACE L. HAYDEN, OF BOSTON, MASSACHUSETTS, ASSIGNOR OF ONE-HALF
TO HENRY C. GOOD SPEED, OF SAME PLACE.

HEAD FOR FABRIC TAKE-UP DEVICES FOR KNITTING-MACHINES.

SPECIFICATION forming part of Letters Patent No. 317,773, dated May 12, 1885.

Application filed March 18, 1884. (No model.)

To all whom it may concern:

Be it known that I, HORACE L. HAYDEN, of Boston, in the county of Suffolk and State of Massachusetts, have invented a new and useful Improvement in Heads for Fabric Take-Up Devices for Knitting-Machines; and I do hereby declare that the following is a full, clear, and exact description of the same.

My invention is an improvement in the swiveled head ordinarily used with that class of circular-knitting machines in which the fabric is drawn upward as the work of knitting progresses.

It consists in the special construction of the swiveling devices, the object being to lessen the friction, to prevent "wabbling," and to prevent also the dripping of the lubricating oil upon the fabric.

In the accompanying drawings, Figure 1 represents in perspective my improved swivel-head. Fig. 2 is a longitudinal vertical section of the same. Fig. 3 is a detail view showing the swivel-rod with its cup in section.

The head A, with the hooks *a a*, is of ordinary construction.

The eye *b* of the swiveling rod B is designed to be attached to a cord which passes over a pulley and is connected to a weight. In the form heretofore used this rod passes through a hole in the center of the head A, and is upset underneath with a suitable interposed washer. This construction causes considerable friction. The parts wear out rapidly, the head soon wabbles, and the oil used to lubricate the swivel drops on the fabric.

In my improved construction I provide the under side of the head with a hollow nipple, *d*, the bore of which is continuous with the hole in the head, and the end of which is beveled annularly, as shown at 1.

On the end of the rod B which is fitted to

pass through the nipple is a cup, D, of such an interior diameter as to receive the nipple and permit it to turn freely therein. The bottom of the annular space between the interior surface of the wall and the rod B is inclined to correspond with the end of the nipple, so that it remains centered after wear. The nipple and cup are both hardened. A groove or annular chamber is formed on the inside of the cup, as indicated at *e*, and thus the capacity of the cup is increased. The cup is filled with oil, which, by the revolution of the head, is properly distributed. The bearing formed by the nipple is long enough to maintain the head in position even after long use and wear.

I claim—

1. In combination with a suitable head, A, having devices for holding the fabric, a swiveling rod passing through the head and provided with means for connecting it to a cord, and with a cup at its lower end, all substantially as described. 60

2. In combination with the head A, the nipple, the rod B, and the cup, all substantially as described. 65

3. In combination with the head A, the nipple having an annularly-beveled end, and the cup with corresponding annular bottom, all substantially as described. 70

4. In combination, the head A, the nipple, the rod B, and the cup having groove or annular chamber on its inner face, all substantially as described. 75

In testimony whereof I have signed my name to this specification in the presence of two subscribing witnesses.

HORACE L. HAYDEN.
